Primary Examiner — Susan Moon Lee(74) *Attorney, Agent, or Firm* — Alan R. Stewart; Stewart IP Law(57) **CLAIM**

I claim the ornamental design for a handle for an electronic device, as shown and described.

DESCRIPTION

FIG. 1 is a perspective view of a handle for an electronic device showing my new design;

FIG. 2 is a front elevational view thereof;

FIG. 3 is a rear elevational view thereof;

FIG. 4 is a left side elevational view thereof, the right side being a mirror image;

FIG. 5 is a top plan view thereof;

FIG. 6 is a bottom plan view thereof; and,

FIG. 7 is a bottom plan view of the main handle alone, shown detached from the round base portion.

Broken lines and portions contained within broken lines are not claimed.

1 Claim, 4 Drawing Sheets(56)
